UNITED STATES PATENT OFFICE.

WILLIAM WATTIE, OF WORCESTER, MASSACHUSETTS, ASSIGNOR TO CROMPTON & KNOWLES LOOM WORKS, A CORPORATION OF MASSACHUSETTS.

LOOP-CUTTING MECHANISM FOR PILE-FABRIC LOOMS.

1,054,952.

Specification of Letters Patent.

Patented Mar. 4, 1913.

Application filed July 18, 1912. Serial No. 710,168.

To all whom it may concern:

Be it known that I, WILLIAM WATTIE, a citizen of the United States, residing at Worcester, in the county of Worcester and 5 State of Massachusetts, have invented certain new and useful Improvements in Loop-Cutting Mechanism for Pile-Fabric Looms, of which the following is a specification.

My invention relates to loop cutting 10 mechanism for pile fabric looms; and more particularly to improvements in mechanism for cutting the loops in the class of pile fabric looms in which needles or wires are used, over which the loops are formed. Said 15 needles or wires extend in the direction of the length of the fabric, and the loops also extend in the direction of the length of the fabric.

In looms of the class referred to, as ordinarily made, there are a series of cutters, 20 which consist of knife blades to be removably supported in holders, which have rounded needle shaped ends, which extend into the loops of the fabric, and the loops 25 are cut by knife blades, as the woven fabric moves toward them, all as fully shown and described in U. S. Letters Patent, No. 758,968, dated May 3, 1904, to which reference is made.

30 In my improvements, I do away with the stationary knife blades or cutters, and substitute therefor sliding blades or cutters, which are located within an opening or pocket, and have a sliding movement therein, 35 in the direction of the length of the fabric, communicated thereto by a rocking or moving bar, which has an oscillating movement in a horizontal plane, and which is operated by mechanism on the loom, and which is 40 adapted to successively move the cutting blades toward the woven fabric, and back again, at regular intervals, to cut the loops of pile. The knife guides or blade holders, which have been made separate from the 45 pile wires over which the pile loops are formed, are in this instance detachably connected to the pile wires, and the pile loops which are formed over the pile wires are held in their extended upright position, all 50 the way to the cutting knife; by this construction the knife holders are easily connected to, or disconnected from the pile wire, in order to remove the knife holders.

I have only shown in the drawings a 55 detached portion of a loom of the class re-

ferred to, with my improvements applied thereto, sufficient to enable those skilled in the art to understand the construction and operation thereof.

Referring to the drawings:—Figure 1 is 60 a plan view of my improved loop cutting mechanism, combined with parts of a loom, looking in the direction of arrow *a*, Fig. 2. Fig. 2 is a section, on line 2, 2, Fig. 1, looking in the direction of arrow *b*, same figure, 65 and also shows a portion of the loom side, and the lay, not shown in Fig. 1. Fig. 3 shows, on an enlarged scale, one end of a pile wire, detached, and the knife holder detachably connected thereto, with a movable cutting blade; the dotted lines show the cutting blade in its backward position. Fig. 4 is a top or plan view of the parts shown in Fig. 3, looking in the direction of arrow *c*, same figure, and, Fig. 5 is a bottom or lower 70 edge view of the parts shown in Fig. 3, looking in the direction of arrow *d*, same figure.

In the accompanying drawings, 1 is the loom side or end frame, 2 is the breast beam, 80 3 is the breast beam plate, extending upon and attached to the upper part of the breast beam 2, on the inside thereof, and over which the pile fabric 4 passes to the take-up roll 5.

6 is the lay, having a rocking motion communicated thereto in the usual way.

7 is the reed, supported on the lay, and 8 is the hand rail on top of the reed 7.

9 is a transverse bar having suitably carried thereon the vertically extending blades or uprights 10 for the pile needles 11. The pile needles 11 extend through the dents of the reed 7 toward the breast beam plate 3, and have the free end 11', over which the 95 loops 4 of the pile warps 4' are formed.

All of the above mentioned parts, except the construction of the pile needles 11 may be of the ordinary and well known construction in looms of the class referred to. 100

I will now describe my improvements.

At the front of the breast beam 2, and secured at each end thereof is a bar 12, which extends transversely across the loom, and has fastened therein, in this instance 105 by screws 13', a transverse bar 13, which, on its inner edge has a downwardly extending lip or flange 13'', or projections thereon, which extend into a slot 14' in the upper part of the knife guides or holders 14, see 110

Fig. 2. The knife guides or holders 14, see Figs. 3, 4, and 5, are in this instance made separate from the pile wires 11, and are preferably made of sheet metal cut in the desired shape and bent along the middle portion, to form an opening or pocket into which the sliding knife blade 15 can be easily inserted. The upper portions of the outer enlarged end of the knife holder 14 are preferably riveted together, as shown at 14'', see Fig. 3.

The extended inner end of the knife holder 14 is flattened at 14'', see Fig. 5, and is adapted to closely fit into a recessed portion 11'' on the pile needle 11, which holds in this instance the end 14'' of the knife holder 14, to form a suitable joint, and also allows the knife holder to be easily detached from the pile needle 11 without re- 20 moving the pile needle.

The cutter or knife blade 15 has one end sharpened and beveled at 15', see Fig. 3, to engage with the loops 4 on the pile fabric, and cut them apart as the knife 15 is 25 moved from the position shown by dotted lines, to the position shown by full lines in Fig. 3. The sliding knife 15 has an upwardly extending projection 15'', which is adapted to extend within the path of, and to 30 be engaged by a rocking or moving bar 16. The bar 16 has an oscillating movement in a horizontal plane, and is provided with two downwardly extending longitudinal ribs 16^a, and 16^b, see Fig. 2. The rib 16^a is 35 of slightly curved shape, shown by broken lines in Fig. 1, and is adapted, on the oscillating movement of the bar 16 in one direction, to successively move the cutters or knife blades 15, to press the loops 4 on the 40 pile fabric, and cut them apart while the other rib 16^b, which is of angular shape, shown by broken lines in Fig. 1, is adapted to reset the knives 15 again at regular intervals. The oscillating bar 16 has its ends 16' 45 loosely carried in U shaped bearings 17' and 18' in sliding blocks 17 and 18, which in this instance are guided at each end of the breast beam 2 in the guide parts 19 and 20, respectively, extending outwardly from the sliding blocks 17 and 18 are arms 17'' and 18'', see Fig. 1, each of which has pivotally connected thereto one end of a link 21, and 22, respectively. The other ends of the links 21 and 22 are each pivotally connected to the 50 upper end of an arm or lever 23, and 24,

which arms have their hubs 23' and 24' loosely mounted on the transverse shaft 25; the ends of said shaft 25 are secured in bearings 26', and 27', on stands 26 and 27, which are secured to the loom side. The hub 23' has an arm 23'' extending downwardly therefrom, see Fig. 2, which has pivotally connected thereto one end of a connector or rod 28; the other end of the connector 28 is connected to some operating mechanism on the loom, not shown, which imparts a rocking movement to the upright lever 23. A second lever 24 is operated by mechanism on the loom, not shown, in a similar way, thus imparting to both levers 70 23 and 24, an alternate rocking movement, to communicate a rocking or oscillating movement in a horizontal plane to the bar 16, and sliding knives 15, at regular intervals.

It will be understood that the details of construction of my improvements may be varied if desired.

Having thus described my invention, what I claim as new and desire to secure by Letters Patent is:—

1. In loop cutting mechanism for pile fabric looms, blades or cutters having a sliding movement in the direction of the length of the fabric, and suitably supported and guided, and means, comprising a bar having a rocking or oscillating movement in a horizontal plane, and means for moving said bar, to communicate a sliding movement to said blades or cutters, to successively move them toward the woven fabric, to cut the loops of pile, and move them back again at regular intervals.

2. In loop cutting mechanism for pile fabric looms, blades or cutters, holders therefor, said holders detachably connected to the pile wires, and said pile wires, said blades or cutters having a sliding movement in the direction of the length of the fabric, and means, comprising a bar having a rocking or oscillating movement in a horizontal plane, to communicate a sliding movement to said blades or cutters, to successively move them toward the woven fabric, to cut the loops of pile, and move them back again at regular intervals.

WILLIAM WATTIE.
